Primary Examiner—Cathy Anne MacCormac
Attorney, Agent, or Firm—Flory L. Martin[57] **CLAIM**

The ornamental design for a combined wing and spring shield for a printer media handling system, as shown and described.

DESCRIPTION

FIG. 1 is a perspective view of a combined wing and spring shield for a printer media handling system showing the spring arm in a compressed position;

FIG. 2 is a perspective view of a combined wing and spring shield for a printer media handling system showing my new design;

FIG. 3 is top plan view of FIG. 2;

FIG. 4 is right side elevational view of FIG. 2;

FIG. 5 is left side elevational view of FIG. 2;

FIG. 6 is a bottom plan view of FIG. 2;

FIG. 7 is a rear elevational view of FIG. 2; and,

FIG. 8 is a front elevational view.
